INJECTOR

Bengt E. Folke, Mamaroneck, N. Y., assignor to
 Nathan Manufacturing Company, New York,
 N. Y., a corporation of New York

Application October 1, 1938, Serial No. 232,720

17 Claims. (Cl. 103—270)

The object of my invention is to simplify the operation of an injector by reducing the number of handles or other devices usually required to admit steam and water thereto and at the same time to control these two supplies by the limits of motion or positions of a single lever in a dependable manner.

Another object is to provide means whereby the amount of steam entering the injector is automatically correlated to the volume of water handled.

A further object is to provide balanced valve means to permit effortless operation and gradual admission of steam into the injector.

Still further objects will become apparent in the following specification and in the drawings in which a preferred embodiment of the invention is shown.

In the drawings,

Fig. 1 shows a front elevational view of an injector and its operating mechanism embodying the principles of this invention as applied to the frame of a locomotive, the latter being shown diagrammatically only;

Fig. 2 shows a fragmentary longitudinal section through the upper part of the injector partly in elevation, the injector being shown in a closed position;

Fig. 3 is a fragmentary sectional view similar to the one shown in Fig. 2 except that the injector is shown in an open or operating position;

Fig. 4 is a plan view of the injector proper;

Fig. 5 is a fragmentary elevational side view of the steam and water operating mechanism shown in a closed position;

Fig. 6 is a fragmentary elevational side view similar to the one shown in Fig. 5 except that the operating parts are shown in the position they assume when the injector is working; and

Fig. 7 is a fragmentary sectional longitudinal view of the water valve in the position which it assumes when the injector should "break".

Like characters of references denote similar parts throughout the several views and the following specification.

Referring to Fig. 2, 10 is the upper part of an injector body provided with a water inlet at 11 and a steam inlet at 12. Injector delivery end and overflow mechanism are omitted, being well-known in the art. A water valve 13 guided at 14 and 15 and seating upon the body at 16 controls the admission of water into a chamber 17. The bottom guide 14 for the water valve 13 terminates in a lower edge 14a. The water valve 13 is provided with a throttling disc 18 at its bot-

tom having an upper edge 18a. A valve stem 19 is yieldingly connected to the valve by means of a gland nut 20 and coil spring 21, resting against a head 22 of the valve stem below nut 20. The chamber 17 is closed at its upper end by a bonnet 23 provided at its top with a stuffing box 24 and having at its bottom an extension into the chamber 17 terminating in a lower edge 15a to provide the guide 15 for the water valve. The water valve spindle 19 is connected by means of a clevis 25 and link 26 to a bifurcated lever 27.

A main steam valve 28 controls admission into the injector from steam inlet 12 making a steam-tight joint at 29 upon a seat 30 having a diverging opening 30a. Steam valve 28 is provided with an extension 31 with an enlarged head 31a having a sliding fit in a central bore at the upper part of a steam nozzle 32.

The upper part of the main steam valve 28 is guided within a sleeve 33 held in place by a cap 34. A stuffing box 35 is provided at the top of cap 34. The upper part of main steam valve 28 is closed by a stop nut 36 loosely fitting around a valve stem 37 to which a pilot valve 38 is connected by means of a nut 39.

40 are transverse steam openings through the wall of the main steam valve 28 above its pilot valve seat. 41 is a restricted annular steam passage formed by the sleeve 33 and the outside of the valve 28. 42 is a reduced portion of the extension 31, its upper part where it is joined to the main valve 28 being provided with inclined transverse steam passages 43 immediately below the pilot valve seat.

Steam nozzle 32 has a central extension 44 around which is screwed a jet nozzle 45 forming an annular steam space 46 therewith which is in communication through passages 47 in the nozzle 32 with the steam supply when the main steam valve or pilot valve is open. Surrounding the extension 44 of the steam nozzle 32 is an intermediate nozzle 48 of the usual construction forming an annular passage 48a therewith.

49 is a bracket secured upon the water and steam valve caps 23 and 34 by clamp nuts 50 and 51. 52 and 53 are standards vertically projecting from the bracket 49 and terminating in sockets 54 and 55 to receive a pin 56 to which a closed end 57 of the bifurcated lever 27 is fulcrummed.

Valve stem 37 of the main steam valve is provided with a clevis 58 at its top which is fastened by means of a pin 58a to a link member 59 and by means of another pin 60 to another link member 61 forming essentially a toggle joint. The link 55

member 61 is fastened to the bifurcated lever 27 by means of a pin 61a. 62 and 62a are stops on member 59, and 63 and 63a are stops on member 61, the stops straddling the pin 60 as clearly shown in Figs. 5 and 6. Externally of the links 59 and 61 upon the pin 60 are fastened, at each end, rollers 64 and 65. 66 and 67 are cams projecting laterally from standard 53 and adapted to engage the rollers 64 and 65 with convex vertical end faces 68 and concave bottom end faces 69 which meet at edge 70.

Referring to Fig. 1, 71 is a hand lever provided with the usual type of latch arrangement to engage with a quadrant 72. Hand lever 71 is provided with a crank 73 connected to a rod 74 for the purpose of raising and lowering injector operating lever 27.

The operation of the injector is as follows:

With the position of the injector hand lever 71 as shown in Figs. 1 and 2, an initial movement 20 of the lever from its closed position lifts rod 74 and operating lever 27, link 26, clevis 25 and water valve stem 19 until the stem head 22 contacts gland nut 20, when a continued movement lifts 25 water valve 13 from its seat 16 admitting water from inlet 11 into chamber 17 and into annular passage 48a around injector steam nozzle 32. A further upward movement of rod 74 fully opens the water valve and brings it to the position shown in Fig. 3.

When the water valve is open, the upward movement of pin 61a which holds the link member 61 to the operating lever 27 will have caused the two link or toggle joint members 59 and 61 to straighten out until stop 63 at the upper member 61 contacts with stop 62 of the lower member 59 after the rollers 64 and 65 have cleared the bottom face 69 and edge 70 of the cams 66 and 67, as shown in Fig. 6. A further upward movement of rod 71 will then cause clevis 58 and valve stem 31 to be moved upwardly raising pilot valve 38 from its seat, permitting steam to enter through the annular steam passage 41 of restricted area, passage 40 and 43 into a steam space 45, whence it enters the radially disposed steam passages 47 in the steam nozzle and is discharged through annular steam passage 46 between jet nozzle 45 and the main steam nozzle extension 44, as clearly shown in Fig. 3. Steam discharged from jet nozzle 45 into passage 48a creates a 50 partial vacuum in the water space 17 in a manner well-known to those familiar with the art. It will be noted that annular steam passage 41 is restricted so as to admit steam at reduced pressure into steam space 45, acting on top of head 31a of steam valve extension 31. This serves to reduce the pressure on the upper area of the head 31a and reduces the upward pull necessary to lift the steam valve 28 from its seat. Continued upward movement of operating rod 74 55 opens steam valve 28, withdrawing head 31a of extension 31 from the steam nozzle 32 and permits the injector to go into operation. While the injector is thus manipulated, its overflow valve 60 is open, and may then be closed by hand, if so desired in order to handle hot water, or it may 65 close automatically as is common to certain types of injectors.

When the steam valve is in wide open position, 70 as shown in Fig. 3, the head 31a of extension 31 will be positioned about central within the steam space 17 and the throttling disc 18 of the water valve 13 somewhat below the water valve opening. In this position it will be noted that the maximum 75 amount of water which may enter the injector

through the water valve is governed by the distance between water valve seat 16 and the lower edge 15a of guide 15.

Further upward movement of rod 74 will serve 5 gradually to reduce the distance between the upper edge 18a of the throttling disc 18 and the lower edge 14a of guide 14, thus reducing and regulating the amount of water entering into the injector water chamber 17. It will also be noted that such additional upward movement 10 will bring the head 31a of steam valve extension 31 into the narrowing or diverging opening in steam valve seat 30, thus also reducing the amount of steam entering into steam nozzles 32 and 46, in the same proportion as the amount of water 15 is reduced by throttling disc 18.

When hand lever 71 is operated to shut off the injector, rod 74 is lowered, forcing steam valve stem 31 and water valve stem 19 downwardly bringing main steam valve 28 and pilot valve 38 20 to their seats, thus shutting off admission of steam from inlet 12.

Collapsible link members 59 and 61 are held in the position where stops 62 and 63 are in contact until the rollers 64 and 65 on pin 60 disengage vertical faces 68 of cams 66 and 67. When the rollers 64 and 65 have passed edges 70 of the cams, additional downward movement of the connecting pin 60 permits link members 59 and 60 to collapse and assume the position shown in 30 Fig. 5, the additional downward movement of the water valve stem 19 bringing the water valve to its seat to shut off the water supply from inlet 11.

In Fig. 7 is shown the position of the water valve 13 which it assumes if the injector should 35 "break" while the overflow valve is closed. The steam in the injector body then exerts a pressure against the bottom of the throttling disc 18 and forces the same upwardly against the tension of the spring 21 until it closes the water valve opening, thus preventing steam from entering the water supply and heating the same unduly. Further downward movement of the lever to close the steam valve 28 will then in turn compress the spring 21 somewhat, there being sufficient space 40 left between its coils, and continued downward motion of the lever 27 will finally close the water valve 13.

While the water valve and throttle disc which latter acts as a check valve are shown in combination with an injector operated by a single 50 lever, the same principle could, of course, be employed with injectors in which the water valve is independently operated, and in which this construction provides a safety feature against steam blow backs into the water supply.

It is also obvious that while I have disclosed the starting mechanism in connection with a vertical type of injector, the same may be applied to horizontal types as well, and moreover may be 60 used with injectors having types of nozzles and dispositions of such different from the one shown.

It is understood that various other changes of form, proportions and minor details of construction may be resorted to without departing from 65 the principles or sacrificing any of the advantages of the invention as defined in the appended claims.

What I claim as new, is:

1. In an injector, a casing, a water valve and 70 a main steam valve secured in laterally spaced relation in said casing and independently removable therefrom, an operating lever connected to open both valves, and mechanical means between the said lever and steam valve to cause the steam 75

valve to open, independent of steam pressure in the injector, after the water valve has been opened.

5 2. In an injector, a water valve and a steam valve, an operating lever having connection to both valves for opening and closing the same, the said connection including a pair of links pivotally connected to the said lever and steam valve, adapted to permit the steam valve to remain 10 closed until the water valve has been opened fully.

3. In an injector, a water valve and a steam valve, an operating lever connected to both valves, and a pair of links pivotally connected to the 15 said lever and steam valve having limited movement with respect to each other adapted, when opening the valves, to permit the steam valve to remain closed until the water valve has been opened fully and, when closing, the water valve 20 to remain open until the steam valve has been closed.

4. In an injector, a water valve and a steam valve, both normally closed, an operating lever connected to both valves, a pair of links pivotally connected to the said lever and steam valve having limited movement with respect to each other adapted to permit the steam valve to remain closed until the water valve has been opened fully, and means to prevent movement of the 30 said links with respect to each other after opening of the water valve to open the said steam valve.

5. In an injector, a water valve and a steam valve, both normally closed, an operating lever connected to both valves, a pair of links pivotally connected to the said lever and steam valve having limited movement with respect to each other adapted to permit the steam valve to remain closed until the water valve has been opened 40 fully, and stationary means to prevent movement of the said links with respect to each other after opening of the water valve to open the said steam valve.

6. In an injector, a water valve and a steam valve, an operating means connected to both valves, including a collapsible pair of links and cams coacting therewith between the said lever and steam valve to force the steam valve to remain closed until the water valve has been opened 50 fully, and to keep the water valve open until the steam valve has been closed.

7. In an injector, a casing having a water opening, a water valve stem extending into the said casing, operating means for the said stem, a water valve yieldingly connected to the said stem within the casing and adapted to close the said opening, and a throttling member projecting from the said valve through the said opening, the said operating means adapted to open the said water 60 valve fully and by continued movement in the same direction bring the said member in throttling relation with the said opening.

8. In an injector, a casing having a water opening and a steam opening, a water valve stem extending into the said casing, a water valve yieldingly connected to the said stem within the casing and adapted to close the said water opening, a steam valve adapted to close the said steam opening, operating means common to both valves, 70 and a throttling member projecting from the said water valve through the said water opening, the said operating means adapted to open the said water valve fully and by continued movement in the same direction bring the said member in throttling relation with the said water opening.

9. In an injector, a water valve and a steam valve, operating means common to both valves, the said water valve being yieldingly connected to the said operating means and adapted to close a water opening, a throttling member projecting from the said valve through the said opening, the said operating means adapted to open the said water valve fully and by continued movement in the same direction bring the said member in throttling relation with the said opening, and a pair of links and cams coacting therewith between the said operating means and the steam valve to force the steam valve to remain closed until the water valve has been opened fully, and to keep the water valve open until the steam valve 15 has been closed.

10. In an injector, a casing having a water opening, a water valve stem extending into the said casing, operating means for the said stem, a water valve yieldingly connected to the said stem within the casing and adapted to close the said opening, and a shut-off member projecting from the said valve through the said opening adapted to close the opening by pressure within the injector operating in a direction opposite to that of the closing movement of the said valve upon a rise of pressure sufficient to cause breaking of the injector while the water valve is in an open position.

11. In an injector, a casing having a water opening, a water valve stem extending into the said casing, operating means for the said stem, a water valve yieldingly connected to the said stem within the casing and adapted to close the said opening, and a throttling member projecting from the said valve through the said opening, the said operating means adapted to open the said water valve fully and by continued movement in the same direction bring the said member in throttling relation with the said opening, the said member adapted to close the said opening by pressure within the injector due to its breaking while the water valve is in an open position.

12. In an injector, a water valve and a steam valve, an operating lever connected to both valves, the said water valve being yieldingly connected to the said lever and adapted to close a water opening, a pair of links pivotally connected to the said lever and steam valve adapted to permit the steam valve to remain closed until the water valve has been opened fully, and a shut-off member projecting from the said water valve, through the said opening to close the opening by pressure within the injector due to its breaking while the water valve is in an open position.

13. In an injector, a water valve and a steam valve, an operating lever connected to both valves, the said water valve being adapted to close a water opening, and a throttling member projecting from the said water valve through the said opening, the said steam valve positioned in and adapted to close a steam opening diverging in shape and having an extension with an enlarged head projecting through the said steam opening, the said member adapted to throttle the said water opening upon movement of the operating lever in the direction to open the valves, while simultaneously the head of the said extension is brought into the said diverging steam opening to throttle the steam opening proportionately.

14. In an injector, a water valve and a steam valve, an operating lever connected to both valves, the said water valve adapted to close a water opening, a throttling member projecting from

the said water valve through the said opening, the said steam valve positioned in and adapted to close a steam opening diverging in shape, and a steam nozzle below the said steam opening, 5 the steam valve having an extension with an enlarged head entering a central bore of the said nozzle, the said member adapted to throttle the said water opening upon movement of the operating lever in the direction to open the valves, 10 while simultaneously the head of the extension of the said steam valve is brought into the diverging opening below the steam valve to throttle the steam opening proportionately.

15. In an injector, a water valve and a steam valve, an operating lever connected to both valves, the said water valve being yieldingly connected to the said lever and adapted to close a water opening, a throttling member projecting from the said water valve through the said opening, 20 the said lever adapted to open the said water valve fully and by continued movement bring the said member in throttling relation with the said opening, a pair of links and cams coacting therewith between the said lever and the said steam valve to force the steam valve to remain closed 25 until the water valve has been opened fully and upon reverse movement of said lever to keep the water valve open until the steam valve has been closed, the said steam valve positioned in and adapted to close a steam opening diverging in 30 shape, and an extension to the said steam valve projecting through the said steam opening having an enlarged head, the said member adapted to throttle the said water opening while simultaneously the head of the said extension is 35 brought into the said diverging steam opening to throttle the steam opening proportionately.

16. In an injector, a main steam valve and a pilot valve, operating means for the said valves, a steam nozzle, the said steam valve having an extension with an enlarged head entering a central bore of the said nozzle, and means to reduce the steam pressure upon the said head including a steam passage of restricted area around the main steam valve in communication with the steam space above the said head after opening of the said pilot valve to facilitate opening of 10 the main steam valve. 5

17. In an injector, a water valve and a steam valve, an operating lever connected to both valves, the said water valve adapted to close a water opening, 15 the said steam valve positioned in and adapted to close a steam opening diverging in shape, a pilot valve within the steam valve, a steam nozzle, the said steam valve having an extension with an 20 enlarged head entering a central bore of the said nozzle, means to reduce the steam pressure upon the said head including a steam passage of restricted area around the steam valve in communication with the steam space above the said 25 head after opening of the said pilot valve to facilitate opening of the said steam valve, the said member adapted to throttle the said water opening upon movement of the operating lever in the direction to open the valves, while simultaneously the head of the said extension is 30 brought into the said diverging steam opening to throttle the steam opening proportionately. 35
